PAPER CONTAINER

Lydia B. Koch, New York, N. Y.

Application February 1, 1938, Serial No. 188,093

5 Claims. (Cl. 229—4.5)

This invention relates to paper receptacles adapted to receive, temporarily retain and finally, freely deliver a liquid in a condition wholly unaffected by the container; specifically, a bottle for the retail sale of milk.

Science has shown that the usual transparent glass milk bottle is detrimental to its contents, due to the passage of light through its walls, the actinic effect of the light causing a chemical 10 change to take place, in degree relative to the time length of its exposure, whereby the taste and odor is affected.

Glass bottles are objectionable also because of high cost, extreme fragility, difficulty, expense 15 and waste of time in rendering them clean and sterile for reuse, cost of re-collection and excessive weight.

Having these matters in mind, it is an object of this invention to provide a paper container, in the form of a conventional milk bottle, having substantially opaque, light obstructive walls that are yieldable under pressure or shock without fracture.

A further feature is in the provision of a container, light in weight, convenient to handle, leak proof and normally sterile, no odor or taste being imparted to its contents, which are retained in pristine, palatable condition.

Another purpose is to produce a paper container capable of economic manufacture from inexpensive material, intended to be discarded after being once used, and presenting a pleasing appearance in color and shape.

These characteristically advantageous objects 35 are accomplished by the novel construction, combination and arrangement of parts hereinafter described and illustrated in the accompanying drawings, constituting an essential component of this disclosure, and in which:

Figure 1 is a side elevational view of a preferred embodiment of the invention.

Figure 2 is a longitudinal sectional view of the same.

Figure 3 is a transverse sectional view taken 45 on line 3—3 of Figure 1.

Figure 4 is a fragmentary view, partially in section, of the upper portion of the bottle, showing the mouth formation.

Figure 5 is a similar view of the bottom portion.

Figure 6 is a fragmentary sectional view taken at the joint between the upper and lower section of the body.

Figure 7 is a plan view of the blank from which the conical upper portion of the bottle is formed.

Figure 8 is an enlarged fragmentary sectional view taken on line 8—8 of Figure 7.

Figure 9 is a sectional view taken on line 9—9 of Figure 7.

Figure 10 is a fragmentary view of a modified blank for the conical upper wall.

Figure 11 is a plan view of the blank for the lower cylindrical wall section of the bottle.

Figure 12 is an enlarged fragmentary sectional view taken on line 12—12 of Figure 11. 10

Figure 13 is a sectional view taken on line 13—13 of Figure 11.

Figure 14 is a fragmentary view of a modified blank for the lower, cylindrical wall of the bottle.

Figure 15 is a perspective view of a blank constituting the bottom of the bottle. 15

Figure 16 is a similar view showing the blank as semi-finished.

Figure 17 is a central sectional view of the bottom as finally formed. 20

Figure 18 is a perspective view of a blank from which the bottle top is made.

Figure 19 is a similar view of the same in a semi-finished condition.

Figure 20 is a central sectional view of the bottle top as completed. 25

Referring in greater detail to the drawings, the lower main body, designated generally by the numeral 25, is indicated as cylindrical, its wall formed by coiling a blank strip of paper 26 so 30 tightly upon itself as to produce, in effect, a unit composed of inner and outer laminae united under such pressure as to cause substantial coalescence, the end edge 27 of the outer coil and its upper edge 28 showing in Figure 1. 35

It is well known that in coiling a strip of paper upon itself, as the blanks 26 and 41, outer end portion of the unconfined strip will stand away from the coil at a tangent, due to the inherent stiffness of the material. 40

In order to overcome this condition, a plurality of rows of nodules 38—38' are arranged in staggered, spaced relation in the strips, prior to winding, these nodes or humps preferably being elongated, spaced impressions, although the impressions may be continuous, formed to extend outwardly from the adjacent surface of the coil and of such depth as to cause dilation and expansion of the outer surface, due to the stretching effect produced, but insufficient to perforate the paper; then, upon the application of moisture, as from an adhesive, the extending end 27 tends to curl inwardly, towards the coil, rather than away from it, thus facilitating the formation of the cylinder or cone. These nodes or humps, in- 50

stead of being elongated, could be made by letters or numbers so that the name of the company and the patent numbers could be cut into the paper.

5 The lower part of the cylinder thus produced is infolded, as at 31, turned upwardly at 32 and finally directed outwardly towards the wall, as at 33, thereby forming an annular recess 34 of essentially rectangular cross section.

10 The curling of the bottom is facilitated by the formation, in the lower edge of blank 26, of a plurality of closely arranged depressions 35, causing a substantial softening and stretching of the fibers so that the edge portion is rendered more 15 readily yieldable and ductile.

A circular disc 37 shown in detail in Figures 15, 16 and 17 constitutes the slightly concave bottom, the peripheral edge of the disc being corrugated or undulated, as at 38, and curled 20 downwardly upon itself, as at 39, to conform to the annular recess 34 in which it is interengaged and solidly embedded by dies operating from both sides under heavy pressure, as may be noticed by the substantially square outer corner and flat 25 under surface of the edge of the bottle bottom, all crevices being eventually filled with paraffin or similar odorless, tasteless, bland substance whereby a leak proof joint is produced.

The upper element 40 of the bottle is formed 30 in a similar manner, from a crescent shaped blank 41 to constitute a cone, its lower cylindrical portion 42 having its coiled layers spread to receive the outer coil of the upper edge of the body 28 therebetween, while the corresponding 35 inner coil of the body element is disposed inter-jacent the inner coil of the cone.

The interengaging base 42 of the cone blank is preferably rather deeply undulated by angular impressions 35' radiating from the axis 40 of the curved blank, as best seen in Figure 7.

These several layers are condensed and consolidated at their junction by rolling on a mandrel to produce a substantially smooth inner surface and a slightly corrugated outer surface presenting an annular row of indentations causing 45 the fibers of the paper to coalesce and firmly unite the upper and lower portions of the bottle, which is further secured by an adhesive.

The upper portion of the cone 40 is further 50 treated to produce a series of creased undulations 45 constantly increasing in magnitude towards the mouth rim 46 of the bottle, these undulations starting from near the base of the cone and acting to increase its conicity, strength 55 and rigidity, and also to provide an effective grip for the hand.

The rim 46 is expanded to a diameter in excess of the upper end of the cone and presents an arcuately curved outer surface, merging at 60 its upper edge 47 into a downreaching cylinder 48, ending in a firm, flat flanged seat 49 to receive a conventional bottle cap thereon retained by the cylinder.

The inner edge of the seat is downwardly 65 curved to blend into an inner arcuate element 50 disposed closely interjacent the rim 46 and finally turned downwardly, as at 51 adjacent the wall of the cylinder 48, all minute spaces being filled with paraffin after being formed by pressure into the shape indicated.

70 It is to be understood that the joints of the structure are secured by a suitable cementitious adhesive, as is also the folds of the mouth, stiffening the several united elements, so that the initial shape is maintained, and, further, that

the entire interior is treated in such manner as to introduce an impervious lining of some innocuous bland substance, such as paraffin.

It will be noted that the paper blanks 41, shown in Figures 7 and 10, have their upper 5 corners removed to present flat edges 41', thus avoiding excessive thickening at points where these corners would overlap.

Also in Figure 10, the opposite outer corner 41'' is cut out for the same reason, a similar 10 reduced corner 26' showing in Figure 14, the elimination of these corners tending to produce uniformity in the thickness of the completed wall, avoiding difficulty in manufacture and improving the appearance of the product. 15

Figures 18 to 20 illustrate the bottle cap, composed of a disc 55 crenulated as at 56 at its edges, these undulations extending well into the body.

Eventually the cap is shaped between dies to 20 present a flat central portion 57 suited to enter the bottle mouth 48, and rest on the seat 49, its edge forming a semi-circle 58 in cross section, adapted to engage over the rim 47 and extend downwardly, as a skirt 59, resiliently fitting the 25 enlargement 46, due to the flexibility of the skirt wall, which is normally inwardly inclined.

The foregoing disclosure is to be regarded as descriptive and illustrative only, and not as restrictive or limitative of the invention, of which 30 obviously an embodiment may be constructed including many modifications without departing from the general scope herein indicated and denoted in the appended claims.

Having thus described the invention, what is 35 claimed as new and desired to secure by Letters Patent, is:

1. A sectional container composed of volutely laminated tightly rolled two-ply blanks, the contiguous edges of adjoining sections mechanically 40 interleaved to form an interengaged joint said blanks notched at their intersecting corners to avoid an excessively thickened hump in the finished seam.

2. A sectional container composed of volutely 45 laminated, tightly rolled two-ply blanks, each recessed at their intersecting corners, the contiguous edges of adjoining sections of which are mechanically and successively interleaved in the presence of an adhesive and finally rolled under 50 pressure whereby a smooth inner surface and closely corrugated outer surface is obtained at the joint thus formed, the fibers of the paper becoming coalesced.

3. A paper blank for a container element, said 55 blank being arcuately curved at its upper and lower edges and of equal width throughout its length, the ends of said blank presenting uniform angles directed radially to the axis of the curved edges, one of the lower corners being 60 sharply defined, the other notched and the upper corners uniformly horizontal to a radial line bisecting the curved edges.

4. A paper container comprising a cylindrical lower member, a conical upper member, the walls 65 of both members imperforate and composed of at least two convolutions of the blanks, a cylindrical extension on the base of said conical members, the walls of said extension being interleaved with corresponding upper edge portions 70 of said lower member, said interleaved elements being jointly compressed, a series of indentations rolled into the outer surface of the interleaved elements to cause substantial coalescence of the adjoining fibers, the joint thus formed having a 75

smooth interior surface, a raised concave closure permanently fixed in the bottom portion of said lower member, a mouth at the uppermost end of said conical element, and an annular cap receiving seat disposed within said mouth.

5. In a paper bottle, a conical neck comprised of a blank cut in the form of a segment, its inner and outer edges circumscribed by radii having the same focal point and embracing an angle of

ninety degrees, the inner upper corners reduced to present straight edges disposed horizontally with respect to a plane passing through the center of said segment and focal point, and a notch cut in the lower corner of the segment at one end thereof said notch preventing additional thickness of the bottle wall at point of completion of the winding.
